(57) CLAIM

The ornamental design for a football helmet hat, as shown and described in the accompanying drawings.

DESCRIPTION

FIG. 1 is a perspective view of the football helmet hat;
 FIG. 2 is a right side elevation view of the football helmet hat;
 FIG. 3 is a left side elevation view of the football helmet hat;
 FIG. 4 is a front elevation view of the football helmet hat;
 FIG. 5 is a rear elevation view of the football helmet hat;
 FIG. 6 is a top plan view of the football helmet hat; and,
 FIG. 7 is a bottom plan view of the football helmet hat.
 The features shown in broken lines in the drawings illustrate environment that forms no part of the claimed design.
